H. C. BROWN,
SUPPORT FOR SILO LADDERS,
APPLICATION FILED APR. 5, 1915.

1,171,697.

UNITED STATES PATENT OFFICE.

HOWELL C. BROWN, OF MORNING SUN, IOWA.

SUPPORT FOR SILO-LADDERS.

1,171,697.

Specification of Letters Patent. Patented Feb. 15, 1916.

Application filed April 5, 1915. Serial No. 19,255.

To all whom it may concern:

Be it known that I, HOWELL C. BROWN, a citizen of the United States, residing at Morning Sun, in the county of Louisa and 5 State of Iowa, have invented certain new and useful Improvements in Supports for Silo-Ladders, of which the following is a specification, reference being had to the accompanying drawings.

10 My invention relates to silos and particularly to means for supporting ladders in conjunction with the wall of a silo.

The primary object of my invention is the provision of means whereby the ladder 15 may be hung from a support mounted upon the silo, this support being so constructed as to lock the silo ladder in position and prevent any chance of accidental detachment.

20 A further object of the invention is to so construct the supporting means that the ladder may be applied to any portion of the silo, the support being so constructed that when weight is placed upon the ladder, 25 the support will swing inward toward the wall of the silo, thus binding the ladder against the wall of the silo and preventing its detachment from the wall or support.

Other objects will appear in the course 30 of the following description.

In the accompanying drawing forming a part of this application, Figure 1 is a side elevation of a portion of a silo with my ladder holding attachment applied thereto, 35 the ring 7 not being swung to its ladder supporting position under the weight of the ladder; Fig. 2 is a like view to Fig. 1, but viewed in a plane at right angles thereto and showing the weight of the ladder 40 causing a depression of the hoop 7, and therefore the swinging of the hoop downward to cause the ladder to bear against the face of the silo; Fig. 3 is a detail sectional view showing the manner in which 45 the hooks on the ladder engage with the hoop 7; Fig. 4 is a detail sectional view showing the manner of supporting the hoop 7 upon the hoop 3^a.

Referring to these drawings, 2 designates 50 a silo of any ordinary or usual construction and provided with the usual hoops 3. The uppermost hoop 3^a is illustrated as the means for supporting the ladder support. To this end, a plurality of hangers 4 are 55 loosely mounted upon the uppermost hoop 3^a and depend downwardly and outwardly

therefrom. These hangers are shown as formed each with an elongated eye 5 at its inner or upper end and an elongated eye 6 at its lower or outer end. Supported in 60 the eyes 6 of all of the hangers, is a hoop 7 which is normally spaced from the wall of the silo. A ladder 8 of any ordinary or usual construction is provided which is formed upon its legs, adjacent its upper 65 ends, with the outwardly projecting hooks 9 which are adapted to engage over the hoop 7.

From the construction heretofore described, it is obvious that the ladder can 70 be disposed with its upper end between the outer hoop 7 and the hoop 3^a and with its hooks engaged over the outer hoop and that as soon as the weight of a man is placed on the ladder, the hoop 7 will swing inward 75 against the ladder or toward the wall of the silo, thus pressing the ladder against the inner hoops and the silo wall and locking the ladder absolutely securely. It will, of course, be obvious that the ladder may be 80 moved entirely around the silo by shifting it along the hoop 7 and lowering it when the ladder is passing the supports that suspend the outer hoop.

While I have described the hoop 7 as suspended from the hoop 3^a of the silo, yet 85 I do not wish to be limited to this construction as this hoop 7 might be suspended in the manner described from the top of the silo, from the sides thereof, or in any suitable manner. The supporting members 4 may be of any number required and I do not wish to be limited to any specific length for these supports, nor to any specific form therefor. My invention is simple, entirely 90 practical and provides means whereby a ladder may be readily placed or hung from the walls of a silo so that the several hoops thereof may be tightened. It is obvious 95 that when tightening these hoops, it is necessary that the ladder shall be disposed against the wall of the silo and that the ladder cannot be inclined against the wall, without making it difficult to tighten the 100 hoops.

It is, of course, obvious that I do not wish to be limited to any specific form of ladder nor specific form of hooks therefor.

Having thus described this invention, what I claim is:

110 1. The combination with a structure, of a hoop entirely surrounding and normally

equally spaced at all points from the structure but movable into eccentric relation thereto upon the application of weight to one portion of the hoop, and a ladder 5 coacting with the hoop and having sliding detachable engagement therewith.

2. The combination with a structure, of a hoop entirely surrounding and normally equally spaced at all points from the structure but movable into eccentric relation thereto upon the application of weight to one portion of the hoop, and a ladder coacting with the hoop and having sliding detachable engagement therewith, said ladder 10 being disposed with its upper end between the hoop and the wall of the structure whereby the depression of one portion of the hoop under the weight of the ladder will cause the hoop to swing into eccentric 15 position and clamp the ladder between the hoop and the structure.

3. The combination with a structure and a hoop having a greater diameter than the structure extending therearound and suspended therefrom for movement into eccentric relation to the structure, of a ladder slidably and detachably engaging the hoop having outwardly projecting hooks engaging the hoop, the ladder being disposed between the hoop and the wall of the structure whereby on the application of weight to the ladder that portion of the hoop engaged by the ladder will swing inward toward the structure and clamp the ladder toward the structure. 30

4. The combination with a structure and a hoop extending around the structure and disposed against the wall thereof, of a hoop greater in diameter than the first named 40 hoop and entirely surrounding the wall of the structure, hangers pivotally connected to the first and second named hoops and normally extending outward and downward from said structure to support the second named hoop in uniformly spaced 45 relation from the wall of the structure, and a ladder having its upper end provided with outwardly projecting hooks engaging over said second named hoop and disposed between the second named hoop and the wall 50 of the structure.

5. The combination with a silo, of a hoop entirely surrounding the upper end of the silo but normally spaced therefrom, hangers 55 pivotally mounted upon the silo wall nor-

mally extending downward and outward therefrom and flexibly connected to said hoop at a plurality of points whereby the hoop shall be normally supported in uniformly spaced relation to the silo wall but may swing inward at one point when weight is applied to that portion of the hoop, and a ladder having outwardly projecting hooks engaging the hoop and shiftable therealong whereby when the ladder is engaged with the hoop the hoop will swing inward toward the silo and the ladder will be clamped between said hoop and the silo wall. 60

6. The combination with a structure, of a hoop entirely surrounding the structure, links pivotally connected to the wall of the structure, each link at its lower end having an elongated eye through which said hoop loosely passes, the eye being longer than the cross sectional diameter of the hoop, 70 said hoop being thereby flexibly suspended from the structure so that it will normally be uniformly spaced therefrom but may swing inward toward the wall of the structure when weight is applied to one portion 75 of the hoop, and a ladder adapted to engage with the hoop to cause the hoop to swing inward and carry the ladder against the wall of the structure. 80

7. The combination with a building, of a plurality of links disposed at intervals around said building and pivotally supported thereon, said links normally extending outward and downward, each of said 90 links having an elongated eye at its lower end and a hoop entirely surrounding the building and uniformly spaced therefrom, said hoop passing loosely through the eyes of said links and being slidably there- 95 through and movable therein, and a ladder slidable along the hoop and engageable therewith at various points whereby the weight of the ladder will cause that portion of the hoop to which the ladder is applied 100 to swing inward toward the wall of the building, the links permitting the eccentric movement of the hoop with relation to the building. 105

In testimony whereof I hereunto affix my 105 signature in the presence of two witnesses.

HOWELL C. BROWN.
